CLAIM

Jun. 10, 2021 (TW) 110303024

The ornamental design for a display screen with graphical user interface, as shown and described.

(51) **LOC (14) Cl.** **14-04**

DESCRIPTION

(52) **U.S. Cl.**

The sole FIGURE is a front elevation view of a display screen with graphical user interface showing our new design.

USPC **D14/485**

The outmost dot-dashed lines in the FIGURE show a display screen, and form no part of the claimed design.
